UNITED STATES PATENT OFFICE.

ABIJAH T. WILCOX, OF JAMESTOWN, NEW YORK, ASSIGNOR OF ONE-HALF TO EDWARD F. FENTON, OF JAMESTOWN, NEW YORK, AND EPENETUS N. JACKSON.

COMBINATION-WASHBENCH.

No. 805,831.

Specification of Letters Patent.

Patented Nov. 21, 1905.

Application filed November 25, 1904. Serial No. 234,132.

To all whom it may concern:

Be it known that I, ABIJAH T. WILCOX, a citizen of the United States, residing at Jamestown, in the county of Chautauqua and State 5 of New York, have invented a new and useful Combination-Washbench, of which the following, taken in connection with the accompanying drawings, is a full, clear, and exact description.

10 The invention relates to the improvement of the washbench so that it shall become a more useful household convenience, and the objects of my improvement are, first, to provide the main central standard with intersecting inclined slots which shall permit of the drip-board being used in a similar relation to each side of the device in a fixed position; second, the insertion of a partition between the two sides of the standard beneath 15 said drip-board in suitable slots, so that the contents of one tub cannot pass into the other; third, the insertion of a bench board or seat in slots in the folding side or tub supports, which in combination with the partition board of the central standard shall form a seat with a back, and, fourth, the cutting of notches in the folding side pieces and central standard, into which the removable seat or back board can be inserted to hold said central standard at an inclination and the arrangement of the cross-cleats on the parts in such a manner as to form a strong step-ladder suitable for washing windows and like uses about the house.

30 In the drawings, Figure 1 is a plan view of the unfolded washbench with the sides extended. Fig. 2 is a sectional view at line X-X in Fig. 1. Fig. 3 is a sectional view of the upper part of the standard with the drip-board inserted vertically to form the upper part of the back of the seat. Fig. 4 is a side elevation with one side unfolded and the other side folded and arranged for use as a step-ladder. Fig. 5 is a side elevation of the folded washbench. Fig. 6 is an end elevation of the same.

Similar numerals refer to corresponding parts in the several views.

The numeral 10 indicates the central standard, which is formed by vertical ends placed opposite one another and connected by suitable cross-cleats 11 and 12 and a vertical wringer-board 13 at the top. Wringer-board

13 is placed to one side of the center of standard 10 to allow for a vertical slot 14, in which 55 is removably inserted a vertical partition-board 15.

Directly beneath vertical wringer-board 13 the oppositely-inclined intersecting slots 16 are cut on the inner sides of the end boards 60 of standard 10 to receive the drip-board 17. Drip-board 17 is so loosely fitted in slots that constant moisture will not cause it to swell to such an extent that it cannot be instantly removed and inserted in the oppositely-inclined 65 intersecting slots to deflect the water to the opposite side of the standard. Drip-board 17 can also be removed from intersecting slots 16 and inserted vertically, as shown in Fig. 3, forming the upper part of the vertical back 70 formed by boards 15 and 17.

The folding bench or tub supports 18 are attached on the outer sides of standard 10 to fold onto the same, as shown in Figs. 4, 5, and 6, and when so folded parts 18 are held 75 in place by suitable buttons 19 on standard 10, which buttons extend out over the parts when folded. The tub-supports 18 are pivotally attached at 20 on the outer sides of central standard 10, the cross-cleats 12 being placed just below said points of pivotal attachment and extending out, so that supports 16 rest upon the cleats 12 when unfolded. The upright supports or legs 21 for the outer end of supports 18 are pivotally attached near the outer ends of 85 the supports 18, and the cross-cleats 23 are so placed as to engage the under side of supports 18 when the supports 21 are brought down to the desired angle of incline. A further cross-cleat 22 connects the two uprights of the supports 21 and gives added stiffness to the supporting-uprights by forming a frame of the two cross-cleats 22 and 23 and the uprights. On the inner side of the side pieces of the supports 18 I cut a lengthwise groove 24 and 95 removably insert a seat or bench board 25, which gives added strength and stiffness to the tub-supports 18 and may be used as a seat. I also cut notches 26 on the inner side of the side pieces of the support 18 and corresponding notches 27 in the edges of standard 10. It is now apparent that by removing one of the seat-boards 25 or the vertical backboard 15 and inserting it at an incline in notches 26 and 27, as shown in Fig. 4, the central standard 10 is held at an angle of incline suitable 100 105

for a step-ladder, and the cross-cleats 11, 22, and 23 form three steps for the same, which are of sufficient height for washing windows and like uses about the house. The upper 5 cross-cleat 23 is arranged to come opposite the lower edge of drip-board 17, as shown in Fig. 4, and the drip-board thus forms a broad upper step to stand upon. The wide base of the central standard, the brace, and the unfolded 10 tub-support 18 hold the ladder exceptionally firm to stand upon.

I claim as new—

1. In a washbench, a central standard composed of two uprights and connecting cross-cleats, a vertical wringer-board in the top of said standard, intersecting slots on the inner sides of said uprights beneath said wringer-board, a drip-board removably inserted in said slots, vertical slots on the inner sides of said 15 uprights, a partition slidably mounted in said vertical slots beneath said drip-board, and folding benches pivotally attached on opposite sides of said standard, substantially as and for the purpose specified.
2. In a washbench, a central standard composed of two uprights and connecting cross-cleats, a partition or backboard vertically secured between said uprights, folding bench side pieces pivotally attached on opposite sides 20 of said central standard, leg-supports pivotally attached near the outer ends of said bench sides to fold onto the same, lengthwise slots on the inner sides of said bench sides, and seat or bench boards removably inserted in said 25 slots.
3. In a washbench, a central standard composed of two uprights and connecting cross-cleats, bench side pieces pivotally attached on opposite sides of said central standard, leg- 30 supports pivotally attached near the outer ends of said bench sides to fold onto the same,

lengthwise slots on the inner sides of said bench sides and seat-boards removably inserted in said slots, cross-cleats on said legs and uprights arranged to form steps, and notches 45 in said bench sides and uprights to receive one of said removable seat-boards in a bracing position between said parts to hold said uprights at an incline, substantially as and for the purpose specified. 50

4. In a washbench, a central standard 10 composed of two uprights and connecting cross-cleats 11 and 12 on opposite sides, a vertical wringer-board 13 in the tops of said uprights, intersecting slots 16 on the inner sides 55 of said uprights beneath board 13, a drip-board 17 removably inserted in said slots, vertical slots 14 on the inner sides of said uprights, a partition-board 15 removably inserted in said vertical slots, folding bench side 60 pieces pivotally attached on opposite sides of said uprights to bear on the cross-cleats 12, folding legs 21 pivotally attached near the outer ends of said side pieces, cross-cleats 23 near the upper end of legs 21 to bear against 65 the under surface of sides 18 and cross-cleats 22 near the lower ends of legs 21, slots 24 on the inner sides of the side pieces and seat-boards 25 inserted in said slots, and notches 26 and 27 in said sides and uprights, to receive 70 one of said seat-boards 25 in a bracing position to hold the uprights in an inclined position, substantially as and for the purpose specified.

In testimony whereof I have signed my 75 name to this specification in the presence of two subscribing witnesses.

ABIJAH T. WILCOX.
